ABSTRACT OF THE DISCLOSURE

A 3-phenyl-4-acyloxy carbostyryl of the formula:

wherein R is methyl or ethoxy prepared by treating 3-phenyl-4-hydrocarbostyryl with an acylating agent, which is useful as a minor tranquilizer with less side effect and low toxicity.

The present invention relates to 3-phenyl-4-acyloxy carbostyryls, and their production and use.

The said 3-phenyl-4-acyloxy carbostyryls are represented by the formula:

[I] 40

wherein R is methyl or ethoxy and include specifically 3-phenyl-4-acetoxy carbostyryl and 3-phenyl-4-ethoxy carbonyloxy carbostyryl.

The 3-phenyl-4-acyloxy carbostyryls [I] exert a taming effect in fighting mice. The test results on 3-phenyl-4-acetoxy carbostyryl [I: R=CH₃] and 3-phenyl-4-ethoxy carbonyloxy carbostyryl [I: R=C₂H₅O] as well as some structurally related compounds and a commercially available minor tranquilizer, chlordiazepoxide, are shown below.

Test method

Ten male mice of *dd* strain weighing 18 to 20 g. each were used and divided into 5 groups each consisting of a pair. Two mice were put on an electrical stimulator and a 200 ml. beaker was placed upside down over the mice. Electric stimulation was given at the intervals of 7 sec. (540 v., 3 ma.). The time until two mice began to fight was measured with a timer at various times after administration of the test compound and calculated in terms of the score of 1 to 9 respectively for 0 to 5 sec., 6 to 10 sec., 11 to 15 sec., 16 to 20 sec., 21 to 25 sec., 26 to 30 sec., 31 to 35 sec., 36 to 40 sec. and more than 40 sec. The dosage showing an average mark of 5 was taken as ED₅₀.

2

Results

Test compound:	ED ₅₀ (mg./kg., per os)
3-phenyl-4-acetoxy carbostyryl	11.5
3-phenyl-4-ethoxy carbonyloxy carbostyryl	10.5
3-phenyl-4-hydroxy carbostyryl	>100
3-phenyl-4-propionyloxy carbostyryl	96.0
3-phenyl-4-phenacyloxy carbostyryl	>100
3-phenyl-4-benzoyloxy carbostyryl	>100
3-phenyl-4-propoxycarbonyloxy carbostyryl	96.0
3-phenyl-4-phenyloxy carbonyloxy carbostyryl	>100
1-ethyl-3-phenyl-4-acetoxy carbostyryl	>100
1-ethyl-3-phenyl-4-ethoxy carbonyloxy carbostyryl	>100
1-methyl-3-phenyl-4-hydroxy carbostyryl	>100
1-ethyl-3-phenyl-4-hydroxy carbostyryl	>100
Chlordiazepoxide	18.0

From the above table, it is seen that 3-phenyl-4-acetoxy carbostyryl and 3-phenyl-4-ethoxy carbonyloxy carbostyryl show a higher taming effect than chlordiazepoxide, whereas other structurally related compounds exhibit no material or only slight effect.

In addition, it is advantageous that the 3-phenyl-4-acyloxy carbostyryls [I] are less effective in muscle relaxation, which is considered as an unfavorable side action for the use of tranquilizers. For instance, when orally administered to mice, the ED₅₀ values of 3-phenyl-4-acetoxy carbostyryl and 3-phenyl-4-ethoxy carbonyloxy carbostyryl are respectively 113.0 and 117.0 mg./kg. whereas the ED₅₀ value of chlordiazepoxide is 45.3 mg./kg.

It is also advantageous that the toxicity of the 3-phenyl-4-acyloxy carbostyryls [I] is extremely low. For instance, when the acute toxicity is determined by administering orally to mice, the LD₅₀ values of 3-phenyl-4-acetoxy carbostyryl and 3-phenyl-4-ethoxy carbonyloxy carbostyryl are both more than 3,000 mg./kg., whereas the LD₅₀ value of chlordiazepoxide is 1,325 mg./kg.

Thus, the 3-phenyl-4-acyloxy carbostyryls [I] of the present invention are useful as minor tranquilizers with less side effect and low toxicity.

A clinical dosage of the 3-phenyl-4-acyloxy carbostyryls [I] depends on disease syndrome, body weight, age and administration mode, but it is generally in the range of 0.05 to 500 mg./day, preferably of 0.5 to 200 mg./day. They can be used in a unit dosage form as tablets or capsules for oral administration or optionally in combination with suitable adjuvants such as calcium carbonate, starch, lactose, talc, magnesium stearate, carboxymethyl cellulose and gum acacia. Further, they can be formulated into aqueous alcohol, glycol, oil solutions or oil-water emulsions for oral administration in the same manner as conventional medical substances are formulated.

According to the present invention, the 3-phenyl-4-acyloxy carbostyryl [I] is prepared by subjecting 3-phenyl-4-hydroxy carbostyryl of the formula:

[II]

to acylation. The acylation may be accomplished in one or two steps.

When carried out in one step, the 3-phenyl-4-hydroxycarbostyryl [II] or its monoalkali metal salt (e.g. sodium salt, potassium salt) is treated with the reactive derivative of acetic acid or of carbonic acid ethyl ester in the presence or absence of a basic catalyst such as organic tertiary amine (e.g. pyridine, triethylamine, dimethyl-aniline) at a temperature from 10 to 200° C., preferably from 20 to 120° C. The reactive derivative may be acid halide, acid anhydride, nitrophenyl ester, thiocyanate, di-thiocarbamate, tri thiophosphonate or the like. If necessary, there may be employed as the reaction medium an inert organic solvent (e.g. benzene, toluene, dioxane, carbon tetrachloride).

When carried out in two steps, the 3-phenyl-4-hydroxycarbostyryl [II] or its monoalkali metal salt (e.g. sodium salt, potassium salt) is first reacted with phosgene or nitro-substituted phenoxy carbonyl chloride (e.g. p-nitro-phenoxy carbonyl chloride) in an inert organic solvent (e.g. dichloromethane, chloroform, dioxane, tetrahydrofuran) at a temperature from -10 to 30° C. and the resultant 4-chlorocarbonyloxy compound is then reacted with ethanol in the presence of a basic substance such as alkali metal (e.g. sodium, potassium) or alkoxide of alkali metal (e.g. sodium ethoxide) at a temperature from 10 to 60° C. to obtain the 3-phenyl-4-acyloxy carbostyryl [I: R=C₂H₅O].

Practical and presently preferred embodiments of the present invention are illustratively shown in the following examples.

EXAMPLE 1

Preparation of 3-phenyl-4-acetoxycarbostyryl

A mixture of 3-phenyl-4-hydroxycarbostyryl (5 g.), acetic anhydride (40 ml.) and pyridine (0.5 ml.) is heated on an oil bath at 120 to 140° C. for 2 hours. The reaction mixture is allowed to stand at room temperature overnight and concentrated under reduced pressure to remove acetic anhydride. The residue is recrystallized from methanol to give 3-phenyl-4-acetoxycarbostyryl (4.2 g.) as crystals melting at 252 to 254° C.

EXAMPLE 2

Preparation of 3-phenyl-4-acetoxycarbostyryl

A mixture of 3-phenyl-4-hydroxycarbostyryl (2 g.), pyridine (20 ml.) and acetyl chloride (2.5 g.) is heated on a water bath for 2 hours. The reaction mixture is allowed to stand at room temperature overnight and concentrated under reduced pressure to remove pyridine. The residue is recrystallized from methanol to give 3-phenyl-4-acetoxycarbostyryl (1.9 g.) as crystals melting at 252 to 50 254° C.

EXAMPLE 3

Preparation of 3-phenyl-4-ethoxycarbonyloxy carbostyryl

To a solution of sodium hydroxide (169 mg.) in water (30 ml.), there is added 3-phenyl-4-hydroxycarbostyryl (1 g.), and ethyl chlorocarbonate (550 mg.) is dropwise added thereto. The resultant mixture is stirred at room temperature for 30 minutes. The precipitated crystals are collected by filtration and dried. The crystals are dissolved in chloroform and chromatographed on neutral alumina (5 g.). The eluate is concentrated and recrystallized from methanol to give 3-phenyl-4-ethoxycarbonyloxy carbostyryl (450 mg.) as crystals melting at 217 to 218° C. (decomp.).

EXAMPLE 4

	Materials:	Grams
3	3 - phenyl - 4-ethoxycarbonyloxy carbostyryl	5
5	Lactose	65
10	Starch	9.5
15	Microcrystalline cellulose	20
20	Magnesium stearate	0.5

The above materials are mixed together, granulated and tableted in accordance with a conventional method to give 2,000 tablets, each weighing 50 mg.

What is claimed is:

1. A 3-phenyl-4-acyloxy carbostyryl of the formula:

wherein R is methyl or ethoxy.

2. 3-phenyl-4-acetoxycarbostyryl.

3. 3-phenyl-4-ethoxycarbonyloxy carbostyryl.
